UNITED STATES PATENT OFFICE.

VICTOR ALEXANDRE PERLAT, OF LEVALLOIS-PERRET, FRANCE, ASSIGNOR TO SOCIÉTÉ EN NOM COLLECTIF G. MOREUX & CIE., OF PERRET, FRANCE, A FRENCH COMPANY.

DOOR CLOSING AND FASTENING APPARATUS.

Application filed August 21, 1925, Serial No. 51,701, and in France May 6, 1925.

The present invention relates to an automatic and powerful door closing and fastening apparatus, characterized in that it is constituted by a resilient lever arm, rocking about an axis belonging to one of the parts to be connected. This resilient arm is constituted by a pivoted barrel which combines, on the one hand, with a resilient push piece placed within this barrel (the spring acting between the said push piece and the bottom of the barrel) and taking a bearing on the other of the parts to be connected, on the other hand through an outer sliding sleeve which hooks on the whole of the system. The sliding sleeve therefore, when it is hooked on, holds the system in operative position and the push piece takes a bearing on the bottom of the barrel for realizing the stress necessary for assembling the parts to be connected.

This system is moreover combined with a locking mechanism permitting, at will, to render the sliding sleeve and the pivoting barrel rigid with each other, so as to prevent any fraudulent operation. For that purpose, the sliding sleeve carries a lock the bolt of which can receive either a movement of translation, or a movement of translation combined with a rotation, so as to enter into a staple provided on the pivoting barrel.

In the accompanying drawing and by way of example:

Fig. 1 is a vertical section of the improved closing device in accordance with the features of the present invention, the locking device being in inoperative position.

Fig. 2 is a corresponding view thereof, during the actuation of the locking device.

The closing apparatus is essentially constituted by a barrel *c* carrying a side lug pivoted at *g* between the arms of a fork piece *a* rigid with one of the parts to be connected. In this barrel *c* is arranged the resilient push piece *e* on which acts a spring *d* taking a bearing, on the other hand, on the bottom of the barrel *c*. Externally to the barrel *c* an operating sleeve *h* can slide which carries at its inner part a heel piece *i* capable of entering into one of the notches *b* provided on the arms of the fork piece *a*.

The sliding sleeve *h* has a side boss 1 the bore of which is partially screw threaded for receiving the outer screw thread of a bolt *m*. This bolt is provided with driving

pins parallel to its axis of symmetry. These pins fit freely into holes *o* formed in a washer *p* also arranged in the bore of the boss 1. Between the bolt *m* and this washer *p* is interposed a spring *q*. The washer *p* has an entrance opening *p*¹ the depth of which is less than its thickness and a central aperture *p*². In its edge is formed a notch *p*³ directed according to a generatrix and in which enters, at rest, a claw *r*¹ belonging to the fixed plate *r* which closes the bore of the boss 1. This plate *r* has also an entrance opening *r*² and a pivoting dust protector *r*³. In inoperative position, the parts occupy the position illustrated in Fig. 1. The bolt *m* is withdrawn from the staple *s* carried by the rocking barrel *c*; the spring *q* pushes back the washer *p* which is immobilized in position owing to the engagement of the claw *r*¹ in its notch *p*³. The screw *m* is prevented from rotating by the pins *n* which enter into the washer *p*.

For locking the system, the operating key *t* is introduced in the entrance openings *r*², *p*¹ of the plate *r* and of the washer *p*. From this fact, the key-bit *t*¹ pushes back the washer *p* and releases its notch *p*³ from the claw *r*¹. As the washer *p* is then free to rotate, it can be actuated by the bit *t*¹ of the key *t*. It actuates, in its turn, through the pins *n*, the bolt *m* which screws in the screw threaded part of the boss 1 so as to enter into the opening *s*. The rocking barrel *c* is thus rendered rigid with the sleeve *h* and the spring *d* relaxes so as to push back the push-piece *e* downwardly. The head of this push-piece is thus pressed against the member which is to be held stationary.

For releasing the member to be held stationary from the action of the resilient push piece *e*, the key *t* is introduced in the key holes *r*²—*r*¹ of the plate *r* and of the washer *p*, until, as above described, it is possible to impart to the bolt *m* a displacement capable of releasing it from the opening *s* of the rocking barrel *c* (position of Fig. 2). By then imparting to the whole of the system an angular displacement towards the left-hand of the finger, about the axis *g* as pivot, the heel-piece *i* is released from the notch *b* provided in the fork piece *a*. The sleeve *h* can then be drawn upwards so as to constitute a lever allowing to rock towards the right-hand of the figure, the rocking bar-

rel *a* and the resilient push-piece *e*. This push piece thus releases the member which it previously held stationary.

It will be noted that, after closing and after having removed the key *t*, the spring *q* acts for producing the translation of the washer *p* and the engagement of its notch *p*³ with the claw *r*¹. The system is therefore locked and can not move angularly under the action of the external vibrations.

It is obvious that the method of realization of the lock is given by way of example only and that any other similar means might be used for rendering, at will, the rocking barrel *c* rigid with the sleeve *h* which internally slides in the same.

What I claim as my invention and desire to secure by Letters Patent is:

1. In a door closing and fastening apparatus, a hollow cylinder open at one of its ends, pivotally mounted on one of the parts to be connected, a small piston sliding within the said cylinder for taking a bearing on the second one of the parts to be connected, a spring arranged in the cylinder, taking a bearing on the upper end of the latter and on the small sliding piston, a hollow sleeve sliding on the said cylinder, a boss on the said sleeve, a notch on the part supporting the articulation of the hollow cylinder for rendering the latter rigid with the said part, means permitting at will, to render the sleeve rigid with the said hollow cylinder.

2. In a door closing and fastening apparatus, a hollow cylinder open at one of its ends, pivotally mounted on one of the parts to be connected, a small piston sliding within the said cylinder for taking a bearing on the second one of the parts to be connected, a spring arranged in the cylinder, taking a bearing on the upper end of the latter and on the small sliding piston, a hollow sleeve sliding on the said cylinder, a boss on the said sleeve, a notch on the part supporting the articulation of the hollow cylinder for rendering the latter rigid with the said part, a boss on the said sleeve, a sliding bolt in the said boss for permitting to render, at will, the sleeve rigid with the said hollow cylinder.

3. In a door closing and fastening apparatus, a hollow cylinder open at one of its ends, pivotally mounted on one of the parts to be connected, a small piston sliding within the said cylinder for taking a bearing on the second one of the parts to be connected, a spring arranged in the cylinder, taking a bearing on the upper end of the latter and on the small sliding piston, a hollow sleeve sliding on the said cylinder, a boss on the said sleeve, a notch on the part supporting the articulation of the hollow cylinder for rendering the latter rigid with the said part, a boss on the said sleeve, a screw thread in the said boss, a screw threaded nut screwing on the said screw thread and carrying a

bolt, an opening in the hollow cylinder for allowing the said bolt to enter therein at will in order to render the sleeve rigid with the hollow cylinder.

4. In a door closing and fastening apparatus, a hollow cylinder open at one of its ends, pivotally mounted on one of the parts to be connected, a small piston sliding within the said cylinder for taking a bearing on the second one of the parts to be connected, a spring arranged in the cylinder, taking a bearing on the upper end of the latter and on the small sliding piston, a hollow sleeve sliding on the said cylinder, a boss on the said sleeve, a notch on the part supporting the articulation of the hollow cylinder for rendering the latter rigid with the said part, a boss on the said sleeve, a screw thread in the said boss, a screw threaded nut screwing on the said screw thread and carrying a bolt, an opening in the hollow cylinder, and means for allowing the said bolt to enter therein at will in order to render the sleeve rigid with the hollow cylinder.

5. In a door closing and fastening apparatus, a hollow cylinder open at one of its ends, pivotally mounted on one of the parts to be connected, a small piston sliding within the said cylinder for taking a bearing on the second one of the parts to be connected, a spring arranged in the cylinder, taking a bearing on the upper end of the latter and on the small piston, a hollow sleeve sliding on the said cylinder, a boss on the said sleeve, a notch on the part supporting the articulation of the hollow cylinder for rendering the latter rigid with the said part, a boss on the said sleeve, a screw thread in the said boss, a screw threaded nut screwing on the said screw thread and carrying a bolt, an opening in the hollow cylinder, a locking member arranged in the said boss, rotating together with the nut, but capable of moving in translation relatively to the latter, a spring interposed between the nut and the locking members, and means for rendering the locking member rigid or not with the boss in which it is arranged.

6. In a door closing and fastening apparatus, a hollow cylinder open at one of its ends, pivotally mounted on one of the parts to be connected, a small piston sliding within the said cylinder for taking a bearing on the second one of the parts to be connected, a spring arranged in the cylinder, taking a bearing on the upper end of the latter and on the small sliding piston, a hollow sleeve sliding on the said cylinder, a boss on the said sleeve, a notch on the part supporting the articulation of the hollow cylinder for rendering the latter rigid with the said part, a boss on the said sleeve, a screw thread in the said boss, a screw threaded nut screwing on the said screw thread and carrying a bolt,

- opening in the hollow cylinder, a locking member arranged in the said boss, a second locking member in the said boss, pins on the nut, freely, passing through the said locking member, a spring interposed between the locking member and the nut, a groove in the locking member engaging with a claw of the boss, and means for allowing the locking member to be pushed back and causing the latter as well as the nut to rotate.
7. In a door closing and fastening apparatus, a hollow cylinder open at one of its ends, pivotally mounted on one of the parts to be connected, a small piston sliding within the said cylinder for taking a bearing on the second one of the parts to be connected, a spring arranged in the cylinder, taking a bearing on the upper end of the latter and on the small sliding piston, a hollow sleeve sliding on the said cylinder, a boss on the said sleeve, a notch on the part supporting the articulation of the hollow cylinder for rendering the latter rigid with the said part, a boss on the said sleeve, a screw thread in the said boss, a screw threaded nut screwing on the said screw thread and carrying a bolt, an opening in the hollow cylinder, a locking member arranged in the said boss, a second locking member in the said boss, pins on the nut, freely passing through the said locking member, a spring interposed between the locking member and the nut, a groove in the locking member engaging with a claw of the boss, a plate closing the said boss, a key hole for introducing a key therein in order to allow of pushing back the said locking member and causing the latter as well as the nut to rotate.
